Primary Examiner—Raphael Barkai*Attorney, Agent, or Firm*—Katherine McGuire[57] **CLAIM**

The ornamental design for an eyewear front, as shown and described.

DESCRIPTION

FIG. 1 is a front, perspective view of an eyewear front showing my new design;

FIG. 2 is a front, elevational view thereof;

FIG. 3 is a rear, elevational view thereof;

FIG. 4 is a side, elevational view thereof, the opposite side being a mirror image;

FIG. 5 is a top, plan view thereof; and,

FIG. 6 is a bottom, plan view thereof.

The broken lines appearing in the Figures are for environmental purposes only and form no part of the claimed design.
